UNITED STATES PATENT OFFICE.

JAMES DANIEL PERKINS, OF GREENVILLE, SOUTH CAROLINA.

DESIGN FOR A VALVE-CASING.

SPECIFICATION forming part of Design No. 33,306, dated October 2, 1900.

Application filed September 1, 1900. Serial No. 28,849. Term of patent 7 years.

To all whom it may concern:

Be it known that I, JAMES DANIEL PERKINS, a citizen of the United States, residing at Greenville, in the county of Greenville and State of South Carolina, have invented and produced a new and original Design for Valve-Casings, of which the following is a specification, reference being had to the accompanying drawings, forming part thereof, in which—

Figure 1 is a side elevation showing my new design, and Fig. 2 a plan view thereof.

The leading or material feature of my design consists of the body portion *a*, which is cylindrical in cross-section and slightly conical in form and provided at one side with a coupling *b*, connected with the body portion by a neck *c*, and at the opposite side with a projection *d*, said body portion being also provided at each end with a cylindrical portion *e*, ad-

jacent to one of which at the larger end of the body portion is a groove *f*. The larger end of the casing is also provided with a coupling-head *g* and the smaller end thereof with a nut *h*, and the coupling *b* and the coupling-head *g* are octagonal in form.

Having fully described my invention, what I claim as new, and desire to secure by Letters Patent, is—

The design for a valve-casing herein shown and described.

In testimony that I claim the foregoing as my invention I have signed my name, in presence of the subscribing witnesses, this 29th day of August, 1900.

JAMES DANIEL PERKINS.
